Inventor.

UNITED STATES PATENT OFFICE.

CHARLES GILBERT HAWLEY, OF CHICAGO, ILLINOIS.

STEEPLED RADIANT-HEAT STEAM BOILER.

Application filed March 12, 1924. Serial No. 698,728.

This invention relates to improvements in steam boilers and furnaces; and comprising an especially desirable and novel high pressure steam boiler of the type first disclosed in my co-pending application Ser. No. 643,731, which has since become U. S. Patent No. 1,486,888, issued March 18, 1924. The specific purpose of this application is to patent certain modified forms and structures which could not be specifically claimed in said patent for the reason that another specific form had been selected to be claimed therein.

In common with the parent invention the objects of the present invention are to harmonize the best conditions for the substantially smokeless combustion of "long flaming" fuels with the best conditions for the highly efficient transmission of the heat to the boiler water, including a rapid circulation of the latter; and generally to increase the capacity and efficiency of such boilers, to relatively reduce their size and their cost, to make them safer, simpler to maintain more durable, and, more quickly and certainly responsive to varying furnace temperatures and rates of combustion.

With these and other objects in view my invention provides a boiler with an underlying combustion chamber or furnace space of a height that permits the flames of such fuel to rise to substantially complete maturity before the gases leave the combustion chamber, thus enabling a most complete and efficient burning of the fuel at any desired rate; and concurrently, my invention insures an efficient and maximum transmission of heat to the boiler water through the medium of a minimum number of boiler heating elements of surfaces and without resort to abnormally high furnace temperatures, this being accomplished by operatively dividing the boiler into two sections which perform substantially distinct duties, the first section directly absorbing the radiant heat of combustion within the combustion chamber and comprising complementary boiler elements which are within said chamber and are of such limited number, form and arrangement as to greatly subdivide the body of flame and present considerable surfaces thereto and yet avoid premature extinguishment of the flames, while the other section of the boiler is devoted to the absorption of the

heat of the combusted and non-flaming gases from the combustion chamber.

In conformity with such conception the heating elements which are located within the combustion chamber are of limited number and small area and yet are fully adequate to the absorption of substantially all of the radiant heat of the fire. By accepting the greater part of the heat in this state, it becomes possible to secure an increased efficiency and steaming capacity or without loss of efficiency to greatly reduce the total heating area of the boiler as compared with present boilers and the quantity of fuel burned.

As will presently appear the action of the water and steam in the radiant heat absorbing elements causes a definite and rapid circulation of the water throughout the boiler; not alone in the radiant heat absorbing elements but also upon all of those boiler surfaces which are devoted to the absorption of heat by convection; thus raising the efficiency of those surfaces and making it possible to relatively reduce the extent thereof, or to secure a greater quantity of steam therefrom. The active circulation of the boiler water incidentally enhances the durability of the whole boiler and lessens the maintenance cost thereof.

It should now be evident that my invention takes advantage of the fact that in relation to a given heat absorbing surface, radiant heat is many times more available and effective than the heat of non-luminous hot gases; the heat of flaming gases being transmitted in conformity with the laws of light, while actual surface contact is essential to the transfer of heat from merely hot gases.

When such precautions are taken against cooling the burning gases by contact with cold surfaces, the heat radiated by the flaming gases is accepted by adjacent boiler surfaces without materially reducing the temperature of the flame and without interrupting the chemical combination and self-ignition of the continually supplied combustibles. Thus it appears that by my invention the greater part of the heat available in the fuel may be transmitted to the boiler water through radiant heat absorbing elements or water courses of relatively small extent; leaving the conservation of the re-

sidual heat of combustion to be performed by the more extensive supplementary surfaces of the boiler. The foregoing statement concerning the virtual non-reduction of 5 flame temperature is not to be confused with the reduction of the flame-body, which of course diminishes toward the top; that is, as the combustion proceeds to maturity.

The gases derived from a substantially 10 complete combustion, such as here indicated have a higher temperature than those from a suppressed and incomplete combustion, and volume for volume contain a greater amount of available heat. Only by combustion 15 is the heat liberated, and a suppressed combustion necessarily falls short of liberating all the heat of the fuel. Applying these facts, it seems evident that the residual, non-flaming gases from the combustion 20 chamber of a boiler embodying my invention must needs pass to the convected heat section of the boiler at higher temperatures than usual; and, that the thermal efficiency 25 of that section of the boiler is much increased; again making it possible, comparatively, to reduce the total heat absorbing area thereof or conversely to secure more steam therefrom.

The foregoing statements are applicable 30 to long-flaming fuels of all kinds and hence I here call attention to a feature of my invention which has a special relation to ash-containing fuels. It appears that by my invention it becomes possible to fully utilize 35 the heat of many such fuels while working the furnace at temperatures effectively below the fusing or slagging point of the fuel ash. As by this method it is feasible to do so without detriment to the described sus- 40 tained combustion, I advise as standard procedure the provision of slightly more absorbing surface within the confines of the combustion chamber than actually required for the absorption of all the radiant heat of the 45 fire. The computation follows well-known rules; the cost of the additional surface is negligible; and, the superabundant surface becomes a substitute for the shortened time element that enters into a higher tempera- 50 ture forced combustion of a fuel making it possible to avoid a violently hurried combustion that would fuse the ash and result in clinker troubles or in the deposition of slag on the heating surfaces of the boiler. 55 In explanation of these statements it may be noted that the degree of combustion being the same in both cases, as much heat is liberated by a low temperature flame as by one of high temperature, only the more rapid delivery of the heat being in favor of the latter. As there is now no lack of radiant heat-absorbing surface closely adjacent the sub-divided flame body in the combustion chamber, a hurried combustion is no longer 60 required for the sake of boiler capacity; and

where desired it is possible to conduct the active combustion at temperatures which avoid the slagging of the fuel ash and make certain of a full recovery of the heat in the described sections of the boiler. Starting 70 with a known furnace temperature directly above the grate or other source of fire, the temperature diminishes as the top of the combustion chamber is closely approached and the best practice is to design the combustion chamber and the distribution of heat absorbing elements therein so that normally the gases which are extinguished by the exhaustion of combustion and have radiated 75 their quota of heat, shall enter the convected heat section of the boiler at corresponding temperatures, no effort being made to pass into that section either burning gases or such that have temperatures greatly exceeding 80 the ignition temperature of the combustibles in the lower part of the chamber; thus the highest efficiencies are insured. Under these new and favorable conditions it appears that the requirement for excessive furnace temperatures no longer exists and that 85 generally the factor of furnace temperature need be considered only in relation to a desired rate of combustion within a combustion 90 chamber of given size and with respect to the heat resisting and insulating character 95 of the combustion chamber walls.

All of the described heat absorbing elements and surfaces obviously receive heat by convection but for the sake of clearness I have disregarded the convection values of the 100 relatively small radiant heat section of the boiler.

Further objects of the present invention are to embody the above defined structures, 105 functions and effects in a sectional or unit type steam boiler of a height which shall not be excessive; which may be supported from below, as contrasted with suspension from its top; which shall be almost wholly composed of water tubes and yet so constructed that every tube shall be freely accessible from the interior of the boiler; and, which shall be particularly constructed and designed to operate under the highest pressures required, without entailing the employment 110 of the excessively thick walls that characterize the steam drums and parts of the high pressure steam boilers commonly used.

Further, the present application has particular relation to steam boilers of steeped form in which the heat absorbing and water circulating elements or tubes of major extent, for absorbing the convected heat, are substantially horizontal and all positioned 115 above the chamber in which the radiant heat is efficiently developed and transmitted to the heat absorbing and water circulating elements of minor extent. Boilers embodying 120 the present invention are best built in unit 125 130

form; that is, in sectional parts having vertical header drums of cylindrical form and with such headers comprising much or all of the back and front walls of the boiler furnace and setting; and, which sections are of sizes convenient for transportation and erection. The boiler also is well adapted for efficient firing. And as already indicated, it does away with the necessity for heavy drums of large diameter which are usually necessary on high pressure steam boilers, and on the contrary, may embody relatively small drums and water tubes and still meet all the requirements of the high pressures. 10 marking the present trend of boiler practice. The arrangement of the heat absorbing headers and water circulating tubes is convenient for erection, renewal and repair and facilitates the insertion, removal or repair 15 of arches and baffle walls; and, also provides the necessary space for superheater elements, where such are used. In addition the circulating elements are so disposed and arranged as to provide for the most rapid 20 separation of steam and the rapid circulation and coursing of the water over the surfaces with which it contacts to fully protect the same, all within a minimum of space and with a maximum steaming capacity and efficiency 25 in proportion to the surface area, the number and weight of tubes and other boiler elements utilized.

Briefly, the invention may be defined as comprising a casing or setting containing a tall combustion chamber admitting of the substantially natural maturity therein of the flame of a body and of a long flaming fire, in combination with a steam boiler including wall forming header members of cylindrical form, a major extent of closely spaced heat absorbing circulating tubes horizontally connecting the upper portions of said header members and positioned above said chamber to receive the hot gases therefrom, and a minor extent of widely spaced heat absorbing circulating tubes extending between the lower parts of said header members and serving to subdivide the flame in the combustion chamber to thereby increase its radiant area and yet permit it to rise to substantially natural maturity in said chamber, thus allowing the development of maximum heat from the fuel burned and the absorption by said header members and tubes of minor extent of radiant heat therefrom and correspondingly reducing the heat absorbing duty of said major extent of the boiler. The invention also comprises many novel combinations of parts and numerous details of construction, also as hereinafter described and claimed.

The invention will be more readily understood upon reference to the drawings that form part of the specification. Due to their small size the drawings are necessarily some-

what diagrammatic in character but they show all the elements and essentials of the invention and will be clearly understood by those who are skilled in the arts of combustion, boiler making and boiler operation. 70

Further, for sake of brevity and clearness, such parts as the steam gages, the water gages, blow-off valves, off going steam lines, feed water pipes and the like, have been omitted from the drawings. The application and use thereof is too well understood to require detailed description. 75

For the convenient understanding of the usual proportions of my boilers, I have made the accompanying drawings on the scale of one-quarter inch to the foot, (reduced in the printed patent) and generally these proportions may be relied upon; but I wish it to be understood that my invention is by no means limited thereto or to the precise structures illustrated or to the precise proportions or arrangements of parts; for as will become obvious, my invention is capable of embodiment in many other detailed forms which are comprehended within the scope of the invention as herein described and claimed. 80 85 90

In said drawings Fig. 1 is a vertical longitudinal section of my novel high pressure boiler of the vertical drum type and in the best form thus far devised; the section being upon the line 1—1 of Fig. 2; Fig. 2 is a compound rear elevation and section of the boiler with the part of the covering or casing removed and the left hand half of the view being in section upon the line 2—2 of Fig. 1; and, Fig. 3 is a horizontal section; one-half on the line 3—3 of Fig. 1 and the other half on the line 3^x—3^x of Fig. 1, the better to depict the close and wide spacings of the water tubes which respectively comprise the lower and upper parts of the boiler. 95 100 105

The pressure vessel or boiler proper here disclosed is of an extremely simple form; very rugged; and so constructed that its parts may freely expand and contract under varying degrees of heat, without endangering or destroying the structure. It stands upright upon a framework and base which supports the boiler and which base also encloses the furnace chamber proper; that is, the space in which combustion is initiated. This vertical position of the drum becomes possible by reason of the enforced circulation of the boiler water, as hereinafter described. 110 115 120

The boiler is chiefly characterized by front and rear header drums, 164 and 165, which stand upon end, that is vertically, and are connected by many vertical rows of substantially horizontal water tubes, 166 and 167. 125 It is desirable by reason of the high pressures to be sustained that the header drums, 164 and 165, shall be of small diameter. They are, therefore, only large enough to permit the free entrance of a workman and 130

the comfortable performance of the work which he has to do within them. The diameter of the drums obviously is a measure of the width of the individual boiler, which 5 comprises two such drums and the groups of tubes, 166 and 167. Such a unit may comprise the complete boiler and will operate satisfactorily above a fire chamber of corresponding width. But the grate or fire chamber of common dimensions is of greater width than this and hence the present complete boiler is preferably composed of a plurality of the above described sections or units, all supported by a common framework 10 and base structure and enclosed by common side walls as well illustrated in Figs. 2 and 3. These units are interconnected as by short cross tubes 168 for the sake of free cross circulation between the units; that is, to insure 15 common water levels therein.

Incidentally, the cross-tubes, 168, furnish convenient and stable supports for the wedge-shaped brick, 169, that fill the spaces between respectively adjacent upright header drums. Obviously, the drums 164 and 20 165, comprise the chief parts or major portions of the front and back walls of the boiler. The brick are held in position and the joints are closed by metal face plates, 25 170.

At the bottom of each drum is a step bracket, 171; and, the drums or headers thus find support on the strong cross girders, 172. The latter are preferably outside of the walls 30 35 which form the furnace chamber and therefore are protected from the heat of the fire. The remaining details of the construction of the furnace proper and of the boiler setting as a whole will be clearly apprehended upon examination of the drawings.

The drums 164 and 165, have manholes, 40 45 preferably in their tops, as shown in Fig. 1; and, as explained are large enough to allow a man to be lowered into them; and, obviously in that position it is an easy matter for him to work upon the ends of the many tubes, 167, 168 and 169.

The parts, 173, appearing on the face of Fig. 2 and in Fig. 3, are cleanout holes and 50 55 plugs, positioned opposite respective horizontal tiers of water tubes. It is convenient to pass a rotary tube-cleaner through these holes and into the boiler tubes. However, other tube cleaners may be taken or operated through the manholes of the drums.

The upright drums, 164 and 165, of each boiler section or unit, are preferably truly parallel and all of the tubes, 167, extend between them perpendicularly. The tubes, 167, 60 65 therefore, occupy substantially horizontal positions. As shown, the groups of tubes, 167, may be counted in horizontal rows and also in vertical rows. The latter will be referred to as verti-planular groups. The tubes, 167, are of such number as to be closely

spaced, leaving only sufficient room for the free rubbing passage of the hot gases from the combustion chamber. As well shown in Figs. 2 and 3, the ends of the tubes, 167, are bent in horizontal planes, as required for 70 their proper connection with respective vertical drums.

The tubes composing the lowermost horizontal row in the group, 167, are preferably pitched downwardly, from back to front, the 75 better to accommodate one of the arches hereinafter described and to form a cinder pocket, as well shown in Fig. 1.

To generally typify the construction it has been said that the water tubes of the boiler 80 are substantially horizontal, but obviously this expression must be modified or explained when referring to the tubes, 166. The latter are the main circulation promoting tubes of the boiler and are inclined from the point 85 where they leave the drum, 164, to the higher points at which they enter the drum, 165. This pitch is sufficient to permit the free escape of the mixed steam and water from the tubes, 166, and into the drum, 165. 90

The entire space measured from the lower part of the furnace proper to the groups of tubes, 167, comprises the tall combustion chamber before mentioned and within this chamber the flames develop virtually without restraint by reason of the illustrated verti-planular arrangement and wide spacing of the tubes, 166. The spaces between the verti-planular groups thereof are wide enough to admit a man. This is provided for convenience in assembling and repairing the boiler and more particularly for the purpose of forming upright and free flame passages of such width as to permit the rise of flames therethrough; and, the persistence of ignition 100 105 temperatures quite to the top of the combustion chamber. Obviously also, the verti-planular groups 166, present adequate radiant heat absorbing surfaces; and, the physical presence of such groups within the combustion chamber serves to subdivide the flame arising from the furnace and to thus greatly increase the superficial or radiant surface of the flame body. Thereby it is made possible to communicate a maximum 110 115 of heat to the tubes, 166; it is made possible to accomplish the substantially complete combustion of fuel and, it is made possible to deliver the gaseous products of combustion to the lower part of the group of tubes, 120 167, at substantially the highest temperatures attained in the combustion chamber.

Whenever necessary or desirable the length of flame and gas travel among the tubes may be increased by installing partial 125 fire-brick floors or arches in staggered relation upon the several horizontal rows of tubes; for example, as shown in Fig. 1.

Obviously the construction above described and which comprises two vertical 130

drums and the many tubes connecting them, is duplicated or represented in each boiler unit here shown. And in addition, the several units are interconnected so that 5 common water levels are preserved therein.

The assembled units installed within the side walls, are provided with a common roof or top and have a common breeching or stack connection.

10 When ready for operation the boiler is filled with water to about half the height of the group of tubes, 167. During operation, under the effect of the fire in the combustion chamber, steam is rapidly evolved in the inclined tubes, 167, and, a rapid circulation of water is promoted, first upward therein and within the drums, 165, thence across to the drums, 164, through the tubes, 167, and thence downward, for re-entrance to the 15 20 radiant heat absorbing tubes, 166.

The steam bubbles are not immediately disengaged in the drums, 165, and hence the level of the mixed water and steam in those drums rises to a greater height than does the 25 level of the substantially solid column of water occupying the drums, 164. As the output of steam increases this effect is increased and more and more of the tubes, 167, are called upon for the return of the water 30 from the drums, 165, to the drums, 164.

Much disengagement of steam obviously occurs at the tops of the drums, 165, but also much of the disengagement takes place within the tubes at the top of the group, 167. The 35 uppermost tubes, 167, during proper operation receive only so much water as is entailed by the priming of the steam in the drums, 165, while at lower levels, the tubes, 167, distinctly operate after the manner of a 40 flash boiler.

Thus, in every part, the boiler operation takes advantage of the best possible conditions for the transmission of the heat of the fire to the boiler water, and in consequence, 45 boilers of this design, as measured by the extent of heating surface, will be found to be of much greater capacity and of higher efficiency than the boilers now commonly in use.

The free space above the water in the drums, 164, is of such altitude and of such volume that ample opportunity is given for the precipitation of moisture from the steam and in consequence the output of steam at 55 the tops of the drums, 164, is both clean and dry.

It appears to be distinctly advantageous to thus secure within a boiler of relatively low altitude, the many advantages, benefits 60 and effects which characterize the taller

boilers preferred in my aforesaid Patent, No. 1,486,888.

Having thus described my invention, I claim as new and desire to secure by Letters Patent:—

1. The herein described steam boiler unit, comprising a pair of vertical steam and water headers, in combination with a plurality of verti-planular groups of steam and water tubes connecting the upper parts of 70 said headers and perpendicular thereto, and, fewer verti-planular groups of water and steam tubes connecting the lower parts of said headers and inclined in relation to the same and the first mentioned tubes. 75

2. The herein described steam boiler, comprising a plurality of interconnected units, each comprising a pair of upright steam and water headers, in combination with a plurality of verti-planular groups of steam 80 and water tubes, connecting the upper parts of said headers and perpendicular thereto, and, fewer verti-planular groups of water and steam tubes connecting the lower parts of 85 said headers and inclined in relation to the same and the first mentioned tubes.

3. The herein described steam boiler unit, comprising a pair of upright steam and water drums, having manholes and of a size to admit a workman, in combination with 90 a plurality of closely spaced verti-planular groups of steam and water tubes, connecting the upper parts of said drums and perpendicular thereto, and, fewer and hence more widely spaced planular groups of water and 95 steam tubes connecting the lower parts of said drums and inclined in relation to the same and the first mentioned tubes.

4. The herein described steam boiler comprising a plurality of closely spaced and interconnected units, each composed of a pair of upright steam and water drums provided with manholes and of a size to admit a workman, in combination with a plurality of closely spaced verti-planular groups of 100 steam and water tubes, connecting the upper parts of said drums and perpendicular thereto, and, fewer and hence more widely spaced planular groups of water and steam tubes connecting the lower parts of 105 said drums and inclined in relation to the same and the first mentioned tubes. 110

5. A steam boiler as defined in claim 4 and characterized by wall-completing brick between respective drums and partly supported by the means which interconnect said drums. 115

In testimony whereof, I hereby affix my signature.

CHARLES GILBERT HAWLEY.
